(57) CLAIM

The ornamental design for a woman's shoe, as shown and described.

DESCRIPTION

FIG. 1 is a top, front and right side perspective view of the woman's shoe, showing my new design;

FIG. 2 is a top plan view thereof;

FIG. 3 is a right side elevational view thereof;

FIG. 4 is a front elevational view thereof;

FIG. 5 is a left side elevational view thereof;

FIG. 6 is a rear elevational view thereof; and,

FIG. 7 is a bottom plan view thereof.

The broken lines in FIGS. 1–7 are for illustrative purpose only and form no part of the claimed design.

1 Claim, 7 Drawing Sheets
